UNITED STATES PATENT OFFICE.

ROBERT T. VAN NORDEN, OF SAN FRANCISCO, CALIFORNIA.

MOVABLE JETTY.

SPECIFICATION forming part of Letters Patent No. 309,264, dated December 16, 1884.

Application filed June 11, 1884. (No model.)

To all whom it may concern:

Be it known that I, ROBERT T. VAN NORDEN, a citizen of the United States, residing at San Francisco, in the county of San Francisco and State of California, have invented certain new and useful Improvements in Movable Jetties, of which the following is a specification.

My invention relates to improvements in movable or floating jetties, or wing-dams; and the object of my invention is to provide a device whereby the channels and bars of rivers and estuaries may be deepened by the action of the current of outflowing water. This object I accomplish by means of the device illustrated in the accompanying drawings, in which—

Figure 1 is a plan view showing my improved jetty or wing-dam in position. Fig. 2 is a side view of the same. Fig. 3 is a front view. Fig. 4 is a plan view illustrating a modification.

Similar letters of reference are used to indicate like parts throughout the several figures.

A represents the hull of any suitable vessel, ship, or scow, to which the jetty or wing-dams are attached.

B is a short substantial bowsprit, and C C are the cat-heads projecting from the port and starboard bows.

The movable jetty or wing-dams D D are composed of planking or sheet metal suitably backed, braced, and stayed, and are secured in an edgewise or vertical position in any suitable manner to the bow or cut-water of the vessel by either hinges or bolts; and the rear edges or ends of these jetty-boards are beveled off, as shown in Fig. 2, in order to conform to the degree of rake or inclination given to the bow or stem of the vessel. These jetty-boards project forward from the bow of the vessel in a diverging manner, or at an angle of, say, about thirty degrees, with a fore-and-aft line drawn through the center of the vessel. The forward lower ends or corners of the floating wing-dams or movable jetties are given an inward curve, warp, or wind, as shown, in order to counteract the tendency of the bow to lift up, caused by the pressure of the increased volume of water produced by the concentration of the current between the converging jetty-boards, and thus the outer or forward

ends of the movable jetty counteract upon or counterbalance the inner or rear end thereof. As the tendency of the descending current of water is to force the jetty-boards farther apart, I connect each side board by braces E E, which are connected to the bowsprit of the vessel, while other braces, F F, extend backward from the said jetty side boards to the cat-heads C C. The jetty-boards can, however, be adjusted as to width and pitch or angle, as desired.

In the modification shown in Fig. 4 the general construction and form of the jetty is the same, with the exception that two vessels are employed, one upon each side of the triangle formed by the jetty-boards and connect thereto by suitable braces. This device is intended more particularly for use in rivers and at the mouths thereof, or in any other place where there is a current setting continuously in one direction; and in operation the vessel is steamed or towed up stream, or is allowed to drop down from above onto the upper side of the sand bar or flat which is intended to be operated upon. The vessel is then made fast by anchorage, or, when in a narrow stream, by spring-lines leading to the shore, and is held in position with the flaring mouth of the jetty pointing up stream. The body of water which now enters the mouth of the jetty will be concentrated as it approaches the apex of the triangle, and as the jetty-boards project high enough out of the water to prevent any overflow or wash, all the water so concentrated will be directed downward beneath the keel of the vessel and a strong current will be produced at this point, sufficient to flush out or wash away the sand or mud and leave a channel of considerable depth beneath the vessel.

When the channel has been cut as deep as the force of the descending current will permit of, the vessel is then lowered down the stream until the end of the channel so produced has been reached, when the vessel is again made fast, and the whole operation is repeated.

From the foregoing it will be seen that I am enabled to provide a floating wing-dam or movable jetty which is of cheap and simple construction, and provide a means whereby sand bars and other similar obstructions in

rivers and estuaries may be easily and quickly removed and the channel-way deepened by the direct action of a concentrated body of water directed upon the obstruction.

5 Having thus described my invention, what I claim, and desire to secure by Letters Patent, is—

A movable jetty consisting of two diverging jetty-boards or wing-dams, D D, set vertically

in the water and connected at their rear ends, to said jetty being secured to one or more vessels, substantially as and for the purpose described.

In testimony that I claim the foregoing I have hereunto set my hand and seal.

ROBERT T. VAN NORDEN. [L. S.]
